UNITED STATES PATENT OFFICE.

LUZERNE A. WILLIAMS, OF SYRACUSE, NEW YORK.

DESIGN FOR AN INSULATING-PLUG FOR ELECTRIC-LINE SUPPORTS.

SPECIFICATION forming part of Design No. 31,838, dated November 14, 1899.

Application filed October 17, 1899. Serial No. 733,930. Term of patent 14 years.

To all whom it may concern:

Be it known that I, LUZERNE A. WILLIAMS, of Syracuse, in the county of Onondaga, in the State of New York, have invented and produced a new and original Design for an Insulating-Plug for Electric-Line Supports, of which the following is a specification, reference being had to the accompanying drawings, forming a part thereof.

- 10 Figure 1 is an elevation of an insulating-plug for electric-line supports embodying my design. Figs. 2 and 3 are respectively top and inverted plan views of said insulating-plug.
- 15 The leading feature of my design consists of an insulating-plug for electric-line supports, which when viewed in front elevation presents substantially the appearance of a T, having the lower end of its upright branch 20 reduced in diameter, and when viewed in plan presents the appearance of substantially circular concentric surfaces and angularly-arranged surfaces inclosed between two of said concentric surfaces.
- 25 A and B are respectively the transverse and upright branches of an insulating-plug embodying my design. The transverse branch A is of substantially the same size from top to bottom, its outline presenting a substantially oblong parallelogrammatic appearance

in elevation and a substantially circular appearance in plan view. The upright branch B is substantially cylindrical and is also of the same size from top to bottom, with the exception of its lower end, which is formed 35 with upper and lower reduced portions b b', the upper portion b being provided with angularly-arranged surfaces b², having their adjacent ends separated and merged in the substantially circular outline of the main body 40 of said branch when viewed in inverted plan, and the portion b' being substantially cylindrical and provided with a spiral raised surface b³.

An insulating-plug for electric-line supports embodying my design presents a pleasing and characteristic appearance.

What I claim is—

The design for an insulating-plug for electric-line supports, substantially as shown and 50 described.

In testimony whereof I have hereunto signed my name, in the presence of two attesting witnesses, at Syracuse, in the county of Onondaga, in the State of New York, this 10th 55 day of July, 1899.

LUZERNE A. WILLIAMS.
